SALUTE

Application filed November 19, 1928. Serial No. 320,269.

The present invention relates to the improvement of the construction of a pyrotechnical device such as a salute or fire cracker so as to improve the product and facilitate its construction.

Desirable features of devices contributory to the above ends are that they should be constructed with a minimum of materials and so that they will produce the maximum amount of noise or flash of explosion that can be gotten from the amount of material used. To this end the salute is so constructed as to confine the charge of explosive firmly within its casing. Under these conditions when the charge has been exploded the gases formed thereby will be held confined in a comparatively small space until a considerable pressure has been built up and when this has reached a point beyond the resistive strength of the enclosing envelope, rupture thereof will occur with a loud report.

A specific embodiment attaining the above objects is illustrated in the accompanying drawings and comprises a tubular member having a charge of powder therein; the ends of the tube being closed by cup-like plugs or wads positioned so as to provide a resisting flange to prevent premature dislodgement of the plugs, or wads. Flanges formed on the edge of the plugs together with the inwardly curved end walls of the tubular envelope are of particular importance in that connection. This construction will be described in detail in the following specification.

Referring to the drawings,

Figure 1 represents a salute formed in accordance with the principles of the present invention.

Figure 2 is a central longitudinal section through a salute such as is shown in Figure 1, showing the end closures in place and in their accustomed relation to each other.

Figure 3 shows a slightly different arrangement of the plugs or wads relative to the tubular container, and

Figure 4 is a disassembled view of the parts of the container showing the relative dimensions of the end closures to the tubular member.

Referring to the drawings in detail, 10

designates a tubular member which may be formed of paper or any suitable material and of any desired thickness, 11 and 12 designate closures for the ends of the tube and 13 designates a fuse connected with one of these closure members. In the construction of the device, the end member 11 is first placed within the tube 10 while it is in the form shown in Figure 4, after which the tubular member 10 is turned on end with the end in which the member 11 is positioned downwardly. The charge of powder represented at 14 is then placed in the tube above the member 11 after which the closure member 12 is inserted above the powder, thus enclosing the powder within the tubular member 10. The members 11 and 12 before assembling with the tubular member 10 are of the cup shape substantially as shown in the drawings, having their peripheral edges 15 and 16.

In consequence of this fact and the fact that the diameter of the plugs or closures 11 and 12 are slightly greater than the diameter of the tubular member 10, causes a frictional connection between the tubular member 10 and the end members 11 and 12 which will hold the parts in assembled position against the ordinary pressure exerted thereon by the weight of the powder contained therein. This resistance however, is not sufficient to produce the maximum detonation when the salute is exploded. In consequence, in the manufacture of the salute after the above steps have been completed, the ends of the tubular member 10 are bent inwardly as shown at 17 and 18 and according to the form of the device as shown in Figure 2, the flange portion of the cup-like plugs are also bent inwardly with the bending of ends 17 and 18 of the member 10.

It will be noted from Figure 2 that these flanges and these ends lie in contact with each other and form a brace against the dislodgement of the plugs. A further feature to be noted in this connection is the rounded cup-like or dome-like shape of the plugs themselves, which form an arch supported by the abutments as described above produc-

ing maximum resistance against the thrust of the gases of combustion caused by the ignition of the fuse 13 and the consequent burning of the explosive 14 within the envelope.

5 The tendency of the pressure of the gas will be to force the domes 19 and 20 of the plugs outwardly. This tendency, it will appear, will cause greater pressure and binding contact between the flanges 15 and 16 and 10 the bend in walls 17 and 18 delaying in this manner the explosion of the cartridge and the consequent escape of the gases into the air, and the more suddenly the explosion takes place, and the greater the pressure at 15 the time of explosion the greater the detonation, and consequently, the greater efficiency of the device for the purpose for which it is intended.

An alternative form of the salute is shown 20 in Figure 3 in which the member 11 is reversed from the position shown in Figure 2, the concave side thereof being presented toward the explosive charge. The flange sides of the plug are in this instance also positioned along the walls of the envelope or cartridge and as in the previous case, the ends of the envelope are turned inwardly toward the axis of the tubular member 10.

The fuse is inserted through an aperture 20 21 formed in the plug 12. This aperture being formed by a punching, and having consequently a roughened edge which will bite into and grip the fuse 13 with sufficient firmness to hold it in place. The firmness 35 of this grip is augmented by the pressure of the aperture against the member 12, when the same is inserted into the end of the tube 10.

The invention has been described in the 40 preceding specification in connection with the ordinary salute or fire cracker. It is to be understood however, that any pyrotechnical device of this character may be manufactured so as to involve the same principles 45 and the present illustrations and description are to be considered merely as representative and illustrative of the application of the principles to a pyrotechnical device.

It will appear from the above description 50 that in the present invention has been provided a device in which a minimum of explosive may be used to produce the desired detonation or flash and that a device has been provided which may be simply and cheaply 55 constructed without the use of glue or other means for fastening the parts together, other than the friction which may be provided between the various parts themselves.

While we have illustrated and described 60 one embodiment of our invention, it will be understood that modifications may be made without departing from the spirit thereof and, hence, we do not wish to limit ourselves to the precise construction set forth but consider that we are at liberty to make such

changes and alterations as fairly come within the scope of the appended claims.

We claim:

1. A salute consisting of a tubular member, cup-like plugs closing the ends thereof and 70 the ends of the tubular member being bent toward the axis of the tube and resting against and conforming with the walls of the cups and a charge of explosive between said plugs, said cups presenting substantially 75 spherical surfaces to said charge.

2. The method of making a salute consisting in frictionally securing a plug in one end of a tube, turning the tube on end with the plug downward inserting a charge of explosive 80 on top of the plug, inserting a fuse carrying plug and simultaneously bending the ends of the tube over the plugs.

3. A salute consisting of a tubular member, cup-shaped plugs disposed in spaced relation to each other within the said tubular member and frictionally secured therein, the ends of the tubular member being slightly 85 curved inwardly for preventing withdrawal of the plugs.

4. The method of making a salute consisting in forcing a cup-shaped plug in one end of a tube having a smaller diameter than the largest diameter of the cup-shaped plug, turning the tube on end with the plug downward, inserting a charge of explosive in the tube, forcing a fuse carrying cup-shaped plug on top of the explosive and then simultaneously bending the ends of the tube over the 90 plugs.

5. A salute comprising a tubular member, a charge of explosive within the tubular member, a plug in one end engaging against the charge and having a flange extending in frictional contact with the tubular member on the side remote from the charge, the said tubular member and enclosed flange being convergingly constricted, and a closure for the other end.

6. A salute comprising a tubular member, a charge of explosive within the tubular member, a plug in one end having a convex side engaging against the charge and having a flange extending in frictional contact with the tubular member on the side remote from the charge, the said tubular member and enclosed flange being convergingly constricted, and a closure for the other end.

7. A salute comprising a tubular member closed at one end, a charge of explosive within the tubular member, a plug engaging against the charge and in frictional contact with the tubular member, said plug and tubular member being tapered to provide progressively increasing resistance to discharge.

In testimony whereof we have signed our names to this specification.

MONT RUTTER.
EMIL E. LECHLER.
